UNITED STATES PATENT OFFICE

EDWARD J. MORIN, OF WILBRAHAM, MASSACHUSETTS

DESIGN FOR AN AUTOMOBILE TIRE OR SIMILAR ARTICLE

Application filed July 15, 1932. Serial No. 44,340. Term of patent 7 years.

To all whom it may concern:

Be it known that I, EDWARD J. MORIN, a citizen of the United States, residing at Wilbraham, in the county of Hampden and State of Massachusetts, have invented a new, original, and ornamental Design for Automobile Tires or Similar Articles, of which the following is a specification, reference being had to the accompanying drawing, forming part hereof.

Fig. 1 is a plan view of a portion of a tire showing my new design.

Fig. 2 is a side elevational view of the same,

Fig. 3 is a transverse sectional view taken on the line 3—3 of Fig. 1, and

Fig. 4 is a side elevational view upon a small scale showing a complete tire with the design applied to a portion thereof.

I claim:

The ornamental design for an automobile tire or similar article as shown.

EDWARD J. MORIN.
